A. TORNEY.

UNITED STATES PATENT OFFICE.

CHARLES R. CARPENTER, OF ROBBINSDALE, MINNESOTA.

HAIR WAVER.

Application filed February 25, 1924. Serial No. 695,047.

To all whom it may concern:

Be it known that I, CHARLES R. CARPENTER, a citizen of the United States of America, and resident of Robbinsdale, county of 5 Hennepin, State of Minnesota, have invented certain new and useful Improvements in Hair Wavers, of which the following is a specification.

This invention relates to certain improvements in hair wavers; and the nature and objects of the invention will be readily recognized and understood by those skilled in the art in the light of the following explanation and detailed description of the accompanying 10 drawings illustrating what I at present consider to be the preferred embodiments or mechanical expressions of the invention from among various other forms, arrangements, combinations and constructions of 15 which the invention is capable within the spirit and scope thereof.

A primary object of the invention is the provision of a simple and efficient hair waver or curler particularly adapted for use with 20 short or so-called bobbed hair, and which is capable of imparting the desired wave or curl to the hair in a minimum of time.

A further object of the invention is to provide a hair waver or curler upon which 25 the hair can be readily and quickly wound into waving position thereon, and from which the hair can be readily unwound and removed after the desired wave is imparted thereto without damage or injury to the hair.

A further object of the invention is to provide a hair waver or curler of simple, light and compact construction capable of quantity production, and in which the cost of 30 production is materially decreased by forming certain elements or members of the waver of identical form and construction so as to be interchangeable and thereby permit of reduction in time of production and assembly.

With the foregoing general objects, and certain other objects and results in view, which other objects and results will be readily recognized by those skilled in the art 35 from the following explanation, the invention consists in certain novel features in construction and in combination and arrangement of elements, as will be more fully

and particularly referred to and specified hereinafter.

Referring to the accompanying drawings:

Fig. 1, is a plan view of a hair waver or curler embodying the invention.

Fig. 2, is a side or edge view of the hair waver of Fig. 1.

Fig. 3, is a plan view showing a portion of the hair in position on and across the body member or frame, with the tongue member in inoperative position.

Fig. 4, is a view similar to Fig. 3, with the tongue member in secured or attached 60 operative position clamping the hair on the body member or frame.

Fig. 5, is a side view of the hair waver with the hair wound into waving position 70 thereon and the binding member in operative attached position on the frame extending across and binding the hair in wound position.

Fig. 6 is a plan view of Fig. 5, showing 75 the binding member in operative position.

The invention is particularly intended for use in imparting a wave or curl to the end portions of short or so-called bobbed hair, and the mechanical expression and embodiment of the invention illustrated herein with is described and explained in connection and as employed with hair of such types for imparting a wave or curl thereto. However, the mechanical expression and use of 80 the invention presented herewith is purely by way of an example to illustrate and explain the principles and various features of the invention, and not by way of limitation, as the invention is capable of use with 85 other hair than the so-called bobbed types and may be mechanically expressed in other forms to meet the requirements and conditions of the intended use, than the form of the illustrated embodiment, as will be obvious to those familiar with this art.

In the illustrated example, the hair waver or curler embodying the invention comprises a substantially flat, elongated rectangular body member or frame 10 having a hair attaching and clamping tongue or member 20 pivotally mounted on one end portion thereof, and a hair binding member 30 pivotally mounted on the opposite end portion thereof. The body member or frame 10 of the 100 hair waver is formed from a strip or length 105

of relatively stiff and substantially rigid, non-flexible material cut away substantially throughout its length to form the opening 11 and provide a substantially rigid, stiff frame. Adjacent the ends of the frame 10 the opposite side members thereof are connected by the webs 12 integral therewith and extending across the frame opening 11 to form the openings 14 at the opposite ends 10 of the body or frame member 10, for a purpose appearing and explained hereinafter.

The hair attaching and clamping tongue 20 is formed, in the present instance of a substantially flat strip or length of flexible, resilient material having a width slightly less than the width of the frame opening 11 and the length of the webs 12 extending thereacross. The tongue 20 is pivotally mounted on the frame 10 in position extending longitudinally thereacross for swinging movement toward and from the frame, by rolling or turning one end of the tongue back upon itself to form the eye 21 fitting over and around one of the frame webs 12, and pivotally confining the tongue on the frame. The eye 21 is formed of an internal diameter larger than the width and thickness of the web 12 on which mounted so as to permit of the tongue being moved or swung laterally to a position with the free end thereof removed from the adjacent end of the frame, as clearly shown in Fig. 3 of the accompanying drawings.

The free end portion of the tongue 20 extends a distance beyond one end of the frame 10, and is bent or inclined outwardly from a point thereon inwardly from the adjacent web 12 to form the laterally offset portion 22 extending over and across the adjacent web 12 and end portion of the frame 10. The outer end of the offset portion 22 is bent or curved inwardly toward the frame 10 to provide the hook 23 having the bill 24 disposed substantially in the plane of the body of the tongue and terminating in a bent up portion or lip 25 disposed at the opening 14 in the end of the frame 10. In operative position the body of tongue 20 is disposed longitudinally of the frame and the offset portion 22 thereof extends through the frame opening 14 over the end portion of the frame with the hook 23 extending around the frame end and the bill 24 and lip 25 received in the frame opening 14 to lock and confine the tongue in position. (See Fig. 2 of the drawings.)

The hair binding member 30 is identical in design, construction and size with the above described hair attaching and clamping tongue 20, and is formed of a substantially flat strip or length of flexible, resilient material similar to that from which the tongue 20 is formed. The binding member 30 is formed at one end with the eye 31 loosely surrounding the opposite web 12 from that

on which tongue 20 is mounted and pivotally confining the member 30 in position extending across the frame for swinging movement thereon. The binding member 30 is so mounted by the eye 31 on the web 12 of frame 10, that it is disposed and extends along and over the side of the frame opposite the side on which tongue 20 is disposed (see Fig. 2 of the drawings), and terminates in the offset portion 32 extending over and across the tongue eye 21 and adjacent end of the frame 10, in a similar manner to that of the offset 22 of the tongue 20. The offset portion 32 of the member 30 extends beyond the adjacent end of the frame and is formed into the elongated hook 33, similar to hook 23 of tongue 20, having the bill 34 extending around the frame end and terminating in the lip 35 received in the adjacent frame opening 14 on the opposite side of the frame 10 from that on which the hook 23 of tongue 20 extends and terminates. The operative binding position of member 30 is similar to the operative clamping position of tongue 20, the member 30 extending longitudinally across a side of the frame 10 (opposite the tongue 20) with the hook 32 extending over the adjacent frame end lip 35 received in frame opening 14 and locking the member 30 in position.

Thus, the hair attaching and clamping tongue 20 and the hair binding member 30 are identical in construction and are interchangeable, with the result that in assembling a hair waver of the invention a material reduction in time is obtained as well as a saving in production costs through decrease in machinery and elimination of steps necessary in manufacturing the elements of which the waver is formed. Further, as will be more fully explained hereinafter, by employing the identical form, construction and mounting of clamping tongue and binding member in the manner above described, it is possible in the use of a hair waver to interchange the functions of these elements, so that it is not necessary in applying the hair waver to select a certain one of the elements in applying the waver to the hair.

In applying the hair waver embodying the invention as above described, the end portion of the hair to be curled is placed across the body member or frame 10 beneath the hair attaching and clamping tongue 20, which is swung outwardly and laterally from the frame. The foregoing position of the hair and the tongue 20 is clearly disclosed in Fig. 3 of the accompanying drawings. With the hair and waver in this position, the tongue 20 is swung inwardly toward the frame until the hook 23 extends over the adjacent frame end and the lip 25 of the bill 24 is received in frame opening 14, as shown particularly in Fig. 2 of the drawings. Due to the formation of the

tongue 20 of resilient material with the offset portion 22, and the interposition of the hair over and between the frame 10 and the tongue, the latter will be under tension and the hook 33 will be maintained in position with the lip 35 confined within the frame opening 14, and the hair clamped firmly between the tongue and the frame. The position of the tongue 20 attaching and clamping the hair in position on the frame 10 is disclosed in Fig. 4 of the drawings. During the hair attaching and clamping operation through the tongue 20, the hair binding member 30 is swung outwardly from the frame to a remote position so as not to interfere with the clamping operation, such as the position of the member 30 shown in Figs. 3 and 4 of the drawing.

After the end portion of the hair is attached and clamped in position on and to the frame, as shown in Fig. 4, the body of the hair to be waved or curled is then wound tightly on and around the frame 10 and the clamping tongue 20, any desired number of turns of the hair being taken. The hair wound on the frame is maintained in tightly wound position and the binding member 30 is then swung inwardly to position bearing on and extending across the hair, and the hook 33 is forced laterally over the adjacent frame end and snapped into position with the lip 35 of the hook bill 34, received and confined in locked position by the frame opening 14, as shown in Figs. 5 and 6 of the drawings. The resilient material binding member 30 in operative position is bent or bowed outwardly by the body of hair wound on the frame, and is under tension and hence bears tightly upon and binds the hair in wound position on the frame. Due to the elongated hook 33 of the binding member the variations in the depth or thickness of bodies of hair wound upon the frame are compensated for, as the hook is capable of considerable play or movement in locked position inwardly or outwardly on the frame end, as will be apparent by reference to the accompanying drawings.

The body of hair wound tightly onto the frame is maintained under continuous pressure by the resilient binding member 30 extending thereacross under tension and the desired wave or crimp is imparted to the hair along the lines at which the hair is bent or curved around the frame, in a minimum of time. The hair waver is readily, quickly removed from the hair without injuring or damaging the hair, by disengaging hook 33 and releasing member 30 for lateral and outward swinging movement, and by disengaging hook 33 of tongue 20 to unclamp the hair ends. It will be noted that in applying the hair waver, due to the tongue 20 and member 30 being identical in construction and mounting, that either of these

members may be employed as the clamping tongue or as the binding tongue, thus eliminating the difficulties attendant the selection and position of a certain specific element in attaching the hair to the waver. 70

The design, construction and mounting of the elements of the invention as above described, permits of producing the hair waver or curler at low cost and in quantities, and while the frame is preferably formed of a substantially flat, relatively rigid material, and the members 20 and 30 of substantially flat highly resilient material, other forms of material having other relative characteristics may be utilized. 80

It is evident that various changes, variations, modifications and substitutions might be resorted to without departing from the spirit and scope of my invention, and hence I do not wish to limit myself to the exact disclosures hereof. 85

Desiring to protect my invention in the broadest manner legally possible, what I claim is:

1. A hair waver embodying a relatively rigid frame, a resilient hair attaching and clamping member pivotally mounted at one end of said frame and disposed longitudinally over one side thereof, and a resilient hair binding member pivotally mounted at the opposite end of said frame and disposed longitudinally over the side thereof opposite said clamping member, each of said members formed at the free end to detachably engage the adjacent frame end and in engaged position permit longitudinal movement of the member, and said members mounted for lateral movement of the free end portions, respectively, toward and from the frame. 105

2. A hair waver embodying a frame, a hair attaching and clamping member pivotally mounted at one end of said frame and formed at its free end to detachably engage the other end of the frame, a hair clamping member pivotally mounted at the opposite end of the frame and formed at its free end to detachably engage the other end of the frame, and each of said members formed with an offset portion extending over the pivotal mounting of the other member with the said members in position engaging the frame. 110

3. A hair waver embodying a frame, and a pair of similar hair clamping and binding members pivotally mounted on opposite ends of the frame, respectively, and extending longitudinally thereacross, each of said members formed at the free end thereof to detachably engage the adjacent frame end and mounted for lateral movement at the free ends, respectively, toward and from the frame. 125

4. A hair waver embodying a frame, and a pair of resilient hair clamping and bind-

- ing members pivotally mounted at opposite ends and extending longitudinally across opposite sides of said frame, respectively, each of said members formed at the free end thereof with an elongated hook portion for detachably engaging the adjacent frame end, said members movable longitudinally of the frame in engaged position of said hook portions, respectively.
10. 5. A hair waver embodying a frame, and a pair of resilient hair clamping and binding members pivotally mounted at opposite ends and extending longitudinally across opposite sides, respectively, of said frame, each of said members terminating in a portion offset outwardly from and formed to detachably engage the adjacent frame end.
15. 6. A hair waver embodying an elongated relatively rigid frame, a pair of resilient hair clamping and binding members pivotally mounted on the frame at opposite ends thereof and extending longitudinally across opposite sides of the frame, respectively, each of said members terminating in a free end portion outwardly offset from the frame, and said offset free end portions formed to provide hooks for fitting over and detachably engaging the frame ends respectively adjacent thereto.
20. 7. A hair waver embodying an elongated substantially rigid frame, a pair of resilient hair clamping and binding members pivotally mounted on the frame at opposite ends thereof and extending longitudinally across opposite sides of the frame, respectively, each of said members terminating in a free end portion outwardly offset from the frame opposite and extending across the pivotal mounting of the other of said members on
25. the frame, and the free end portion of each member forming a hook for extending over and around the adjacent frame end to detachably engage the same and maintain the member in hair clamping and binding position.
30. 8. A hair waver embodying an elongated substantially flat relatively rigid frame centrally open substantially throughout its length, a connecting web forming a pivot pin extending across the frame opening adjacent to and spaced from each end thereof, a pair of substantially flat resilient hair clamping and binding members pivotally
35. mounted on said webs, respectively, and extending longitudinally across opposite sides of the frame, each of said members terminating in a free end portion formed to provide a hook for detachably fitting over and engaging the adjacent frame end, the said hooks formed to extend into the frame opening in engaged position.
40. 9. In a hair waver, a substantially flat relatively rigid open frame, and a substantially flat resilient hair engaging member pivotally mounted at one end of said frame for swinging movement toward and from the frame and for movement laterally with respect to the frame, said member extending longitudinally across the frame and terminating in an elongated hook portion offset outwardly from the frame for extending over and detachable engagement with the adjacent frame end, said elongated hook portion movable longitudinally of the frame in engaged position.
45. 10. As a new article of manufacture, a hair waver comprising an elongated substantially flat rigid material frame, and a pair of similar substantially flat resilient material hair engaging members pivotally mounted at opposite ends, respectively, of said frame, the said members interchangeable in assembly and in operation in assembled position on the frame.
50. 11. In a hair waver, a frame, and a pair of hair clamping and binding members pivotally mounted on the frame at points spaced inwardly from the opposite ends, respectively, of the frame, and each of said members formed at the free end thereof to detachably engage the adjacent outer end portion of said frame.
55. 12. In a hair waver, an open frame, and a pair of resilient material hair clamping and binding members pivotally mounted on the frame at points spaced inwardly from the opposite ends, respectively, of the frame, each of said members formed at the free end thereof with an elongated hook for detachably engaging the adjacent end of the frame extended outwardly from the pivot point of the other member.
60. Signed at Robbinsdale, Minnesota, this 20th day of February, 1924.
- CHARLES R. CARPENTER.
